(57) **CLAIM**

(21) Appl. No.: **29/321,671**

The ornamental design for ring light source, as shown and described.

(22) Filed: **Jul. 21, 2008**

DESCRIPTION

(30) **Foreign Application Priority Data**

May 23, 2008 (CN) 2008 3 0300670

FIG. 1 is a perspective view of a ring light source showing our design;

(51) **LOC (9) Cl.** 26-04

FIG. 2 is a front elevational view thereof;

(52) **U.S. Cl.** **D26/1**

FIG. 3 is a back elevational view thereof;

(58) **Field of Classification Search** D26/1-4;

FIG. 4 is a left-side, elevational view thereof;

313/313, 315, 317, 318, 493; 315/52, 53,
315/56, 57, 58

FIG. 5 is a right-side, elevational view thereof;

See application file for complete search history.

FIG. 6 is a top plan view thereof; and,

(56) **References Cited**

FIG. 7 is a bottom plan view thereof.
